U.S. Appl. No. 13/832,595, filed Mar. 15, 2013 by Ethicon Endo-Surgery, Inc.

(Continued)

Primary Examiner — Wan Laymon(57) **CLAIM**

The ornamental design for a suture tray, as shown and described.

DESCRIPTION

FIG. 1 is a perspective view of a suture tray;
FIG. 2 is a top plan view thereof;
FIG. 3 is a side elevation view thereof;
FIG. 4 is a bottom plan view thereof;
FIG. 5 is a front elevation view thereof; and,
FIG. 6 is an end elevation view thereof.
The broken lines shown in the drawings are included for the purpose of illustrating structural environment and form no part of the claimed design.

1 Claim, 4 Drawing Sheets# US D771,811 S
